CARD CADDY FOR CARD TABLES AND THE LIKE

George M. Corbett, 2400 Via Sonoma,
Palos Verdes, Calif.

Filed Sept. 26, 1963, Ser. No. 76,749

Term of patent 14 years

(Cl. D33—14)

FIGURE 1 is a perspective view of a card caddy for card tables and the like, showing my new design;

FIGURE 2 is a top plan view thereof; and

FIGURE 3 is an end elevational view thereof.

It is understood that the cross hatching extends throughout the entire area indicated.

I claim:

The ornamental design for a card caddy for card tables and the like, as shown and described.
